UNITED STATES PATENT OFFICE.

FELIX DERNEDEEN, OF CHARLEROI, BELGIUM.

ROTARY FURNACE.

1,372,406.

Specification of Letters Patent. Patented Mar. 22, 1921.

Application filed September 16, 1919. Serial No. 324,205.

To all whom it may concern:

Be it known that I, FELIX DERNEDEEN, a subject of the King of the Belgians, residing at 122 Boulevard Audent, Charleroi, Belgium, have invented certain new and useful Improvements in Rotary Furnaces, of which the following is a specification.

The present invention relates to the metallurgical industry in general, and refers more particularly to a new method of constructing revolving furnaces. By "revolving furnace" is generally understood apparatus rotating about an axis either horizontal or more or less inclined to the horizon and coinciding with the axis of the apparatus itself, such apparatus being utilized in industry for carrying out various operations such as drying, roasting or calcining and various chemical reactions, etc.

The arrangement of known rotary furnaces is varied according to the nature of the materials to be treated and the purpose of the treatment under consideration. Thus, for instance, in continuous working furnaces in which charging regularly takes place at one side and discharging at the other, the passage of the material through the apparatus itself is effected sometimes by inclining the axis of rotation, sometimes by opening out the walls of the furnace, that is to say, by adopting the form of a truncated cone, or again by forming helical grooves or slots in the front walls of cylindrical form, etc. In furnaces in which the operation is effected under the action of heat, the constructional arrangements may be considerably varied according to the nature and results of this action. The most difficult condition to fulfil however, is the prolongation of the length of time the material is retained in the furnace, particularly for operations that require a certain period for their proper materialization. In the furnaces as heretofore constructed the length of time the material to be treated remains in the furnace is prolonged by rotating the furnaces so slowly that the rotation is very difficult to carry on, or by increasing to an excessive extent the total length of the apparatus.

The present invention fulfils the condition of a prolonged rotation of the material in the revolving furnace by subdividing the furnace into several tubes, and it multiplies in varying proportions the effects of the simple furnace.

The accompanying drawings give by way of explanation, indications as to the constructional principle of furnaces according to this invention.

Figures 1 to 4 are cross sections of a cylindrical furnace assumed to be solid, in which a varying number of channels or chambers are formed for the material to pass through.

Fig. 5 is an elevation, partially in longitudinal section, of a furnace for the roasting of blende, constructed in accordance with this invention.

Figs. 6 and 7 are cross sections of Fig. 5.

Referring to Fig. 1, a solid cylinder 1, is presumed to be rotating about the central axis in the direction of the arrow. In this cylinder are formed four small cylindrical channels, 1', 1², 1³, 1⁴, arranged symmetrically about the central axis. Assuming that this cylinder revolves about the central axis in the direction of the arrow, as soon as the line 2—2 has moved a little way to the right of the vertical, any material deposited in the cylindrical channel 1' will flow through the inner passage into the cylinder 1². As the revolving continues, this material will have to pass around the cylinder 1², and it will finish this revolution when this cylinder has reached the position that was previously occupied at the start by the cylinder 1', that is to say, after the completion of the revolution of the furnace as a whole. At this moment the material will slip into the cylinder 1³, the same movements will be repeated for its stay in this cylinder, and then for its stay in the cylinder 1⁴. Assuming next that these cylinders 1', 1², 1³, and 1⁴ are each divided throughout their length into equal compartments by means of vertical partitions, and that the communicating passages are so arranged that the first compartment of 1' communicates with the first compartment of 1², the latter with the first of the cylinder 1³, and this latter with the first of the cylinder 1⁴, which cylinder would be in communication with the second compartment of the cylinder 1'. It would follow from this construction that it is necessary for the whole of the apparatus or the original cylinder in which the four small cylinders are engaged, to make four complete revolutions before the material has advanced one compartment. The number of sub-divisional channels may be increased, (see Figs. 3 and 4) and the passages communicating between the various

2
cylinders may be made at the periphery of the cylinder instead of being arranged at the center.

It is not necessary in practice to partition off the sub-divisional cylinders 1', 1'', etc. This imaginary partition is given by way of explanation. In practice the forward movement will proceed as if the partitions existed. The progress or advancement of the material will be obtained by constructing the aperture of the communication passage between the sub-divisional cylinders 1' and 1'' not along a generating line but along a line that diverges slightly toward the back. 15 This advancement may also be obtained by inclining or curving toward the back the face 3-3 of this passage, or the face 4-4 of the cylinder 1''. The amplitude of the advancement may also be varied by repeating 20 on one or more or on all the passages of the various sub-divisional cylinders the device suggested for the first cylinder 1'.

This construction is in practice of great simplicity, and can be readily carried out in refractory materials as required, for example, when applying it to the roasting of ores. Moreover in the particular cases in which there is occasion for providing for heating, a diversity of special channels may be formed in the blocks between the cylinders, enabling the heating to be carried out by means of a gas-producer, which may even serve for several pieces of apparatus at the same time, or by any other device suitable 35 for the object in view.

The furnace illustrated in Figs. 5 to 7 comprises channels of this type. 5 designates the charger and 6 the discharger. 1', 1'', 1''' and 1'''' designate the working cylinders

through which passes the material to be 40 treated; 7 the combustion channels, 8 the inlet for the combustible gases, 9 the returns for the flames, 10 the exit for the smoke, and 11 the exit for the sulfurous gases.

Figs. 5, 6 and 7 are drawn as if the sub-divisional cylinders, the channels, etc., were hollowed out of the material of which a single solid cylinder 1 consists. In practice these various channels and passages are obtained by the juxtaposition of constructional materials which for this purpose, have predetermined and suitable forms and dimensions.

It will be understood that this invention is applicable to a number of industries and 55 in various constructional forms, each different industrial application requiring an appropriate constructional modification.

What I claim and desire to secure by Letters Patent of the United States is:—

1. A revolving furnace comprising a series 60 of channels or chambers arranged around the axis of rotation and connected with one another by means of passages as and for the purpose specified.

2. A revolving furnace comprising a series 65 of channels or chambers arranged around the axis of rotation and connected with one another by means of passages having inclined faces, substantially as described for the purpose specified.

In testimony whereof I affix my signature in presence of two witnesses.

FELIX DERNEDEN.
